UNITED STATES PATENT OFFICE.

LEE S. CHADWICK, OF EAST CLEVELAND, OHIO, ASSIGNOR TO THE CLEVELAND FOUNDRY COMPANY, OF CLEVELAND, OHIO, A CORPORATION OF OHIO.

STOVE.

1,212,901.

Specification of Letters Patent. Patented Jan. 16, 1917.

Application filed July 23, 1914. Serial No. 852,613.

To all whom it may concern:

Be it known that I, LEE S. CHADWICK, a citizen of the United States, residing at East Cleveland, in the county of Cuyahoga and State of Ohio, have invented a certain new and useful Improvement in Stoves, of which the following is a full, clear, and exact description, reference being had to the accompanying drawings.

10 This invention relates generally to stoves which are designed for use with liquid fuel and which are adapted to burn such fuel in places exposed to drafts. Liquid fuel stoves possessing this characteristic are particularly useful for heating exposed places and when so employed are known to the trade as "orchard heaters."

It is the general object of this invention to produce a stove of this kind which is particularly efficient (being capable of operation in places subject to draft without the production of smoke and without any other material detriment to the flame), and which at the same time is extremely economical of production; also to produce a stove of this character which is simple in construction, involving a minimum of parts, and which can be readily assembled and disassembled for packing and shipping; also to produce a stove of this kind which may be conveniently replenished with fuel from time to time; also to produce a stove of the type referred to which is particularly easy to clean and to maintain in operation.

35 With the foregoing general objects in view, the invention may be defined still further and more generally as consisting of the combinations of elements embodied in the claims hereto annexed and illustrated in the drawings forming part hereof, wherein—

Figure 1 represents a vertical sectional view taken through a stove constructed in accordance with my invention; Fig. 2 is a plan view of the stove shown in the preceding figure, certain parts being broken away to reveal the construction therebeneath; Fig. 3 is a side elevation, on a reduced scale, of the stove illustrated in the preceding figures, showing the top and bottom parts of the stove separated, to permit the filling of the reservoir or the cleaning of the parts; Fig. 4 is a view, similar to Fig. 3, with the parts in assembled condition; and Fig. 5 a

view, similar to Fig. 1, of a modified form of the invention.

55

The stove illustrated herein comprises, generally, a combined reservoir and base portion having part of a central-draft burner of the perforated commingling tube type; a cover portion for the reservoir and carrying the other parts of the burner proper, the wick and the wick raiser and a protecting hood; and an extinguishing hood which is adapted to be applied to the other hood to extinguish the flame and to protect 65 the burner parts when the stove is not operating.

The base portion of the stove comprises an annular open-top reservoir consisting of the outer wall 1, bottom wall 2, and central 70 vertical inner wall 3. The outer wall and the bottom wall may be conveniently formed from a single sheet of metal. The inner wall may be united to the inner edge of the bottom wall in any approved manner, as indicated at 4. It extends upwardly, preferably a little higher than the outer wall, where it is bent inwardly to form a horizontal shoulder, as shown at 5, thence upwardly to form a cylindrical wall 6. Above the cylindrical wall 6, the wall 3 may be projected inwardly to form a cap 7, the cap being shown as provided with a central orifice 8. The burner which is to be used in connection with the stove is of the perforated commingling tube type, and the inner tube 9 may be conveniently seated upon the shoulder 5, fitting around the wall 6, to which it may be permanently secured, as by means of "peening" together the contiguous portions of the wall 6 and commingling tube 9, as indicated at 10. The inner commingling tube is of a height sufficient to insure proper combustion and is shown as closed at its top by a cap 11, which is united to the upper end 95 of the tube in any approved manner. The space between the caps 7 and 11 may be provided with a suitable number of transverse baffles or diaphragms 12 (two being shown) each being perforated as shown at 13, whereby the flow of air through the inner wall or central tube 3 and through the inner commingling tube may be limited to the amount necessary to secure proper combustion.

The bottom of the reservoir is shown as 105 provided with a suitable number of legs 14

which may be conveniently formed by straps of metal bent to appropriate shape and secured to the bottom and the outer wall, as by rivets 15.

The second part of the stove consists generally of the annular cover 16 having the outer commingling tube, the protecting hood, the outer wick tube, the wick, and the wick raiser mechanism. The cover 16 is provided with a depending flange 17 forming a skirt overhanging the upper wired edge of the reservoir therebeneath. Between its inner and outer peripheral portions the cover is shown as provided with a plurality of angular straps 18 the bottoms of which may be secured to the cover in any approved manner, the upwardly projecting portions 19 of the straps having secured thereto a frustoconical hood 20, which extends above the tops of the commingling tubes. The base of the hood 20 is substantially flush with the surface of the portion of the cover therewithin, such portion of the cover being preferably projected upwardly into a ring or corrugation, as shown at 21. The inner edge of the cover is projected downwardly, as shown at 22, and the extreme bottom portion 23 is secured to the outer wick tube 24. This wick tube projects a considerable distance above the inner wick tube and is shown as provided at its top with a series of inwardly projecting fingers 25 constituting a stop for the upper edge of the wick. A slight space is provided between the downwardly projecting portion 22 of the cover and the portion of the outer wick tube adjacent thereto which space is adapted to receive the outer commingling tube 26, which may be secured to the parts 40 by "peening" the overlapping metal parts, in the manner employed for securing together the inner commingling tube and the wall 6.

27 denotes a wick, which is inserted in the wick space provided between the tubes 3 and 24. This wick is preferably of considerably less thickness than the width of the space between said tubes, and the inner surface of the wick is engaged by a carrier consisting of a cylindrical band 28 having a plurality of outwardly and upwardly projecting spring fingers 29 which are adapted to engage the inner surface of the wick. The upper end of the wick can be raised until it is brought into engagement with the fingers 25. The bottom of the band or skirt 28 is flared outwardly, as shown at 28^a, and the bottom of the outer wick tube is correspondingly flared, as shown at 24^a. It is preferred to flare the bottom of the wick, and this flaring may be secured by slitting the bottom of the wick, as indicated at 27^a (see Fig. 3).

The band 28 may be conveniently raised 65 and lowered by a pair of diametrically op-

posed straps 30, said straps having their inner ends connected to the flaring skirt 28^a and extending outwardly therefrom a sufficient distance to clear the bottom of the wick, whence they are projected upwardly 70 and have secured to their upper ends a pair of straps 31. These straps project through the cover 16 and are shown as connected to a band 32 which encompasses the burner and hood. About 90° from the point of 75 connection with the straps 31, an extension of the band is pivoted between a pair of lugs 33 secured to and projecting upwardly from the cover, and at a point diametrically opposite such pivot the band is provided 80 with an operating handle 34, which may be conveniently formed from the metal of the band itself.

When it is desired to extinguish the flame, the frustoconical cover 35 may be applied 85 to the stove, the cover being somewhat greater in diameter and height than the hood 20, whereby it may be dropped over said hood, within the band 32, and serve to extinguish the flame, also to protect the 90 burner parts therebeneath. The hood will be provided with a handle 36, for convenience of manipulation.

It will be noted that, in the embodiment of my invention heretofore described, the 95 reservoir, the inner wick tube, and the inner commingling tube with its co-operating air controlling caps and diaphragms constitute one assembly and that the removable cover 16, outer wick tube 24, outer commingling 100 tube 26, wick 27, and the wick raising parts, together with the hood 20, constitute another assembly. The third element which, strictly speaking, is not essential to the operation of the burner, is the hood 35, which 105 serves to extinguish the flame and to protect the parts therebeneath from rain when the heater is not in use.

From the foregoing description it will be apparent that I have produced a stove or 110 heater which is extremely convenient of operation while correspondingly simple of construction and economical of production. The stove consists essentially of but three parts, including the cover or extinguisher 115 35. When it is desired to fill the reservoir, it is necessary only to tilt or lift the cover, as shown in Fig. 3, whereupon the reservoir may be filled from a pail, without the necessity for a funnel or any special filling appliance and without the necessity of observing any particular care, thus facilitating the operation of filling the reservoir. In the case of orchard heaters, where a large number of heaters are in operation at the same 125 time, the time thus saved is a very considerable saving item. Furthermore, the parts are extremely easily assembled and disassembled. Should the commingling or burner tubes require cleaning, this operation can be 130

performed very readily and easily by merely removing the cover from the reservoir. This exposes the outer surface of the inner tube 9 and the inner surface of the outer tube 26, and these surfaces may be quickly cleaned by means of a brush or any other convenient article.

In operation, the wick may be ignited by means of any suitable type of hydrocarbon igniter whereby burning fuel, such as gasoline, may be dropped into the top of the wick tubes, such an igniter being shown in the patent to William R. Jeavons, No. 1,071,749; or the wick may be ignited by raising the cover a sufficient distance to expose the top of the wick above the inner tube 9 to a lighted match or torch. After lighting, the cover may be replaced.

In Fig. 5 there is shown a modification of the invention illustrated in the preceding views, wherein the open top reservoir is provided with a perforated skirt 37 in place of the strap metal legs shown in the other views and wherein the commingling tubes 38 and 39 are not secured to the tops of the inner and outer wick tubes, respectively, and do not form part of the reservoir and the cover assembly respectively. The inner tube is located above the top of the inner wick tube. The outer tube is seated within an annular space 40 surrounding the upper end of the outer wick tube 24^a. The commingling tubes are connected by tie rods 41 extending thereacross, and the commingling tube assembly may be conveniently centered with respect to the tops of the wick tubes 4^a, 24^a and the wick therebetween by means of the vertical wall 42 defining the outer peripheral portion of the annular space 40.

The hood or shield 20^a may be supported from the cover in the same manner as in the modification disclosed hereinbefore, and the combined extinguisher and cover 35 may be provided for the same purposes and used in the same manner as in the preceding modification.

It will be observed that no special wick raiser mechanism is shown in connection with the heater illustrated in Fig. 5. The wick 27 is provided with a band 28, with the spring fingers 29, as described hereinbefore, and the wick may be raised and lowered by hand, the operator grasping the flaring bottom of the band for this purpose when the cover is removed from the reservoir.

It will be observed that, in the modification just described, no diaphragms are provided between the bottom and the top of the inner commingling tube, the bottom of said tube being formed by the cap 43 which is secured to the top of the inner wick tube and which is shown as provided with a series of perforations 44. The upper end of the

inner commingling tube is provided with a cap 45.

The stove or heater shown herein has been found to be extremely efficient in operation, not only in the matter of thoroughly heating the surrounding atmosphere, but in the matter of immunity from smoke and from extinguishment and serious interference by drafts. With a heater such as disclosed herein, it is possible to heat an orchard efficiently, without damaging the fruit or without the necessity for washing the fruit in order to remove therefrom the carbon stains which will be deposited thereon by a smoky flame. While the possession of these advantages necessarily makes the heater peculiarly efficient as an "orchard heater," I wish to be understood as not limiting my invention to this one use, since, because of its efficiency and freedom from smoke, it is applicable to the heating of water, the heating of garages and other inclosed spaces, and is generally useful wherever efficient heating is desired.

While I have described my invention in detail in connection with the modifications illustrated herein, it is to be understood that I do not thereby limit my invention to such details of construction and that these details may be varied, or departed from, more or less, without avoiding the spirit of my invention.

Having thus described my invention, what I claim is:

1. In a stove of the character described, the combination of an open-top reservoir, a tube extending vertically through the reservoir and having a perforated cap at the upper end thereof, a perforated commingling tube mounted on the upper end of the first mentioned tube, with the cap projecting into and extending across the bottom of said commingling tube, a cap for the commingling tube, one or more perforated diaphragms between said caps, a removable cover for the reservoir adapted to rest upon the top of the same, and an outer perforated commingling tube carried by and movable with said cover.

2. In a stove of the character described, the combination of an open-top reservoir, a tube extending vertically through the reservoir and having a perforated cap at the upper end thereof, a perforated commingling tube mounted on the upper end of the first mentioned tube, with the cap projecting into and extending across the bottom of said commingling tube, a cap for the commingling tube, a removable cover for the reservoir adapted to rest upon the top of the same, and an outer perforated commingling tube carried by and movable with said cover.

3. In a stove of the character described, the combination of an open top reservoir, a

- vertical tube extending therethrough, a perforated inner commingling tube extending above the first mentioned tube, a cover which is adapted to rest on top of the reservoir, a 5 perforated outer commingling tube carried by said cover, a tube depending from the cover and forming with the first mentioned tube a wick space, and a wick for said space.
4. In a stove of the character described, 10 the combination of an open top reservoir, a vertical tube extending therethrough, a perforated inner commingling tube extending above the first mentioned tube, a cover which is adapted to rest on top of the reservoir, a 15 perforated outer commingling tube carried by said cover, a tube depending from the cover and forming with the first mentioned tube a wick space, a wick for said space, and means for holding the wick in frictional engagement with one of the wick tubes thereby to maintain the wick in any adjusted position.
5. In a stove of the character described, 20 the combination of a reservoir, a wick tube therewithin, a perforated inner commingling tube above the wick tube, a removable cover for the reservoir, a perforated outer commingling tube carried by said cover, a tube depending from the cover and forming 25 with the first mentioned tube a wick space, a wick between said tubes, and a wick raiser carried by the cover and operatively connected to said wick.
6. In a stove of the character described, 30 the combination of a reservoir, a wick tube therewithin, a perforated inner commingling tube above the wick tube, a removable cover for the reservoir, a perforated outer commingling tube carried by said cover, a tube 35 depending from the cover and forming with the first mentioned tube a wick space, a wick between said tubes, and an adjustable wick retaining device associated with said wick and the outer wick tube.
- 45 7. In a stove of the character described, the combination of a reservoir having an open top and a vertical wick tube extending therethrough, a perforated inner commingling tube extending above the first mentioned tube, a cover removably applied to the reservoir, a tube depending from the cover and surrounding the first mentioned tube and forming therewith an annular wick space, a 50 series of fingers projecting from one of the wick tubes and forming a wick stop, a wick in the wick space, an outer commingling tube extending upwardly from the upper end of the tube carried by the cover, and a wick raiser carried by the cover and having 55 operating means above said cover for raising and lowering said wick.
8. In a stove of the character described, 60 the combination of a reservoir having an open top and a vertical wick tube extending therethrough, a perforated inner commingling tube extending above the first mentioned tube, a cover removably applied to the reservoir, a tube depending from the cover and surrounding the first mentioned tube and forming therewith an annular wick space, a series of fingers projecting from one of the wick tubes and forming a wick stop, a wick in the wick space, an outer commingling tube extending upwardly from the upper end of the tube carried by the cover, and a wick raiser carried by the cover and having operating means above said cover for raising and lowering said wick.
- 65 9. In a stove of the character described, the combination of a reservoir having a wick tube therewithin, a perforated inner commingling tube extending above the first mentioned tube, a cover removably applied to the reservoir, a wick tube depending from the cover and surrounding the first mentioned tube and forming therewith an annular wick space, a wick stop carried by the cover, a wick in the space between the wick tubes, an outer commingling tube extending upward from about the upper end of the outer wick tube, and wick raising mechanism carried by the cover and having operating means for raising and lowering said wick.
10. In a stove of the character described, the combination of a reservoir having a wick tube therewithin, a perforated inner commingling tube extending above the first mentioned tube, a cover removably applied to the reservoir, a wick tube depending from the cover and surrounding the first mentioned tube and forming therewith an annular wick space, a wick stop carried by the cover, a wick in the space between the wick tubes, an outer commingling tube extending upward from about the upper end of the outer wick tube, and wick adjusting mechanism operatively associated with said outer wick tube.
11. In a stove of the character described, the combination of a reservoir having an open top and a vertical tube extending therethrough, a perforated inner commingling tube extending above the first mentioned tube, a removable cover for the top of said receptacle having an opening and a tube projecting downwardly from said opening and forming with the first mentioned tube an annular wick space, an outer perforated commingling tube projecting upwardly outside the depending tube, a wick in the wick space, a wick-engaging device for said wick, a pair of diametrically opposed straps connected with said device and projecting through the cover, and operating means connected with said straps and supported by said cover.
12. In a stove of the character described, the combination of a reservoir having an open top and a vertical tube extending therethrough, a perforated inner commingling tube extending above the first men-

- tioned tube, a removable cover for the top of said receptacle having an opening and a tube projecting downwardly from said opening and forming with the first mentioned tube an annular wick space, an outer perforated commingling tube projecting upwardly outside the depending tube, a wick in the wick space, a wick engaging device for said wick, operating means for said device carried by said cover, and a wick stop coöperating with the upper end of the wick. 70
13. In a stove of the character described, the combination of an open top reservoir having a central vertical tube extending therethrough, a perforated inner commingling tube located above the former tube, a removable cover for the top of the receptacle having a central opening, a tube depending from the said opening and forming with the first mentioned tube a wick space, a perforated outer commingling tube extending upwardly from the top of the depending tube, a wick in the wick space, a wick-raising band in the wick space, and operating means connected with said band and extending through said cover. 75
14. In a stove of the character described, the combination of an open top reservoir having a central vertical tube extending therethrough, a perforated inner commingling tube located above the former tube, a removable cover for the top of the receptacle having a central opening, a tube depending from the said opening and forming with the first mentioned tube a wick space, a perforated outer commingling tube extending upwardly from the top of the depending tube, a wick in the wick space, and a wick-raising band in the wick space. 80
15. In a stove of the character described, the combination of an open top receptacle, a tube extending vertically through the central portion thereof, a perforated commingling tube extending upwardly above said tube, a cover removably applied to the top of the receptacle and having a central opening, a tube depending from said cover and forming with the first mentioned tube an annular wick space, said tube extending upwardly above the wick space and provided with a plurality of inwardly projecting fingers forming a wick stop, a perforated outer commingling tube carried by the cover and extending upwardly from about the upper end of the depending tube, a wick in the annular wick space, and operating connections for raising and lowering the wick extending through and carried by the cover. 85
16. In a stove of the character described, the combination of an open top receptacle, a tube extending vertically through the central portion thereof, a perforated commingling tube extending upwardly above said tube, a cover removably applied to the top of the receptacle and having a central opening, a tube depending from said cover and forming with the first mentioned tube an annular wick space, said tube extending upwardly above the wick space and provided with a plurality of inwardly projecting fingers forming a wick stop, a perforated outer commingling tube carried by the cover and extending upwardly from about the upper end of the depending tube, and a wick in the annular wick space. 90
17. In a stove of the character described, the combination of an open top reservoir having a wick tube therewithin, a perforated inner commingling tube extending upwardly from the upper end of the wick tube, a cover removably applied to the reservoir, a wick tube depending from said cover and forming with the first mentioned wick tube an annular wick space, a perforated commingling tube extending upwardly from the cover and surrounding the first mentioned commingling tube, a wick in the space between the wick tubes, operating means for raising and lowering the wick carried by and extending above the cover, and a hood for the outer commingling tube carried by the cover. 95
18. In a stove of the character described, the combination of an open top reservoir having a wick tube therewithin, a perforated inner commingling tube extending upwardly from the upper end of the wick tube, a cover removably applied to the reservoir, a wick tube depending from said cover and forming with the first mentioned wick tube an annular wick space, a perforated commingling tube extending upwardly from the cover and surrounding the first mentioned commingling tube, a wick in the space between the wick tubes, operating means for raising and lowering the wick, and a hood for the outer commingling tube carried by the cover. 100
19. In a stove of the character described, the combination of an open top reservoir having a central wick tube extending vertically therethrough, a perforated commingling tube carried by said reservoir and extending upwardly from and communicating with the interior of the first mentioned tube, a cover removably applied to the top of the reservoir and having a central depending wick tube arranged to surround the first mentioned wick tube and form a wick space therewith, an outer commingling tube secured to the cover and projecting upwardly therefrom, a wick in the space between the wick tubes, wick operating means adapted to engage the inner surface of the wick and carried by the cover, a hood carried by the cover and surrounding the outer commingling tube, and an extinguisher adapted to be applied to and removed from the cover. 115
20. In a stove of the character described, the combination of an open-top reservoir, 120

a vertical tube extending therethrough, a
perforated inner commingling tube extend-
ing above the first mentioned tube, a cover
which is adapted to rest on the top of the
5 reservoir, a perforated outer commingling
tube carried by said cover, a tube depending
from the cover and forming a space for the
reception of a wick, and means adjustable
with respect to the wick for holding the

wick in frictional engagement with one of 10
the wick tubes thereby to maintain the wick
in any adjusted position.

In testimony whereof, I hereunto affix my
signature in the presence of two witnesses.

LEE S. CHADWICK.
